UNITED STATES PATENT OFFICE.

CHARLES C. NEWTON, OF PHILADELPHIA, PENNSYLVANIA, ASSIGNOR TO
NEWTON MACHINE TOOL WORKS, INCORPORATED, OF PHILADELPHIA,
PENNSYLVANIA, A CORPORATION OF PENNSYLVANIA.

SLOTTING-MACHINE.

No. 823,354.

Specification of Letters Patent.

Patented June 12, 1906.

Application filed February 11, 1901. Serial No. 46,863.

To all whom it may concern:

Be it known that I, CHARLES C. NEWTON, a citizen of the United States, residing in Philadelphia, Pennsylvania, have invented certain 5 Improvements in Slotting-Machines, of which the following is a specification.

The object of my invention is to so construct a slotting-machine that it can be readily moved from one portion of a shop to another and can be clamped in any position on a bed-plate upon which the work is secured.

A further object is to make the machine self-contained by mounting an electric motor on the sliding portion of the machine, so that 15 the machine can be shifted on its own supporting-bed or moved without interfering with the belting.

In the accompanying drawings, Figure 1 is a front view of my improved slotting-machine. Fig. 2 is a side view. Fig. 3 is a broken elevation of the screw-spindle and adjoining part in section. Fig. 4 is a sectional plan view on the line 4 4, Fig. 3.

A is the base-plate, having at the front and 25 rear edges undercut flanges *a a*.

B is the standard of the machine. This standard carries all the moving elements and is arranged to slide upon the base-plate A, having lips *b*, which underlap the flanges *a a*, 30 the lips in the present instance being in the form of detachable plates.

A feed-screw A' is mounted in the base-plate and passes through a nut on the standard B and is shaped at each end so that a lever can be applied thereto to adjust the standard on the base-plate. The standard B is in the form of a box-frame having vertical 35 guide-faces *b'* at the front, upon which slides the carriage D, and on the carriage is the tool-slide E.

F is a vertically-arranged screw mounted in bearings *b²* *b³* on the standard and provided with thrust-washers *f f'*, consisting, in the present instance, of a series of brass and 45 steel plates alternately arranged, each set of washers being inclosed within a casing *f²*, containing a lubricant. The screw F passes through a nut *d*, secured to the carriage D, Fig. 4, so that vertical movement is imparted 50 to the carriage on turning the screw.

At the upper end of the standard B is gearing by which the screw is operated. Near

the upper end of the screw is a collar *f³*, forming part of the screw-rod, and this collar rests on the upper thrust-bearing. The screw-rod extends above this collar, and mounted loosely on this extension and resting upon the collar is a gear-wheel *g*, which meshes with a pinion *g'* on the stud G, projecting from the standard. In the present instance 55 this pinion is mounted on the extended hub of a bevel gear-wheel *g²*, which is loosely mounted on the stud G, and this bevel gear-wheel meshes with a bevel-pinion *g³* on the driving-shaft G', supported by a bracket projecting from the standard. This driving-shaft has, in the present instance, two fast 60 pulleys and a loose pulley.

H is a belt-shifter which may be of any suitable form. In the present instance I 70 have shown it consisting of two independent arms *h h*, controlled by a cam-slide *h'*, arranged to slide in the bracket supporting the shaft G' and controlled by a vertical operating-rod H', connected at its upper end to the 75 slide *h'* through a bell-crank lever *h²* and rod *h³*. The lower end of the vertical operating-rod H' is guided in a bearing *b²* at the base of the standard, so that any vertical movement imparted to the shifter-operating rod H' will 80 be imparted to the shifter, so that the two belts extending from the motor-shaft can be shifted either onto the fast pulleys or the loose pulley to drive the screw in either direction. On the rod H' are adjustable stops *h⁴* 85 *h⁵*, and on the slide D is an arm *d'*, Fig. 4, which is arranged to strike the stops and shift the rod, so as to reverse the screw at the end of each stroke of the slide.

The tool-slide E is mounted on transverse 90 undercut guides of the carriage D, as clearly shown in Fig. 2, and the transverse movement of this tool-slide is controlled by a screw-shaft I, mounted in bearings on the carriage D and engaging a nut on the tool-slide. This screw-shaft has a pinion *i* meshing with a gear-wheel *i'* on a stud projecting from the carriage, and this gear-wheel meshes with a second gear-wheel *i²* on the shaft I' of the carriage, from which is loosely supported 95 the arm *i³*, carrying any desired form of pawl, (not shown,) engaging with the teeth of the gear and turning the same when said arm is moved in one direction and permitting the 100

gear to remain idle when the arm is moved in an opposite direction.

At the side of the standard, as clearly shown in Fig. 2, is a grooved rail J; on which are stop-blocks j j, which can be moved to any position on the rail and secured after adjustment. These stop-blocks are in line with the arm i³, mounted on the carriage, so that as the carriage is vertically reciprocated it strikes first one block on its upward stroke and the other block on its downward stroke. This movement is imparted to the feed-screw of the slide, so that the slide is moved transversely on the carriage.

15 The tool-slide E carries at its lower end the tool-block K, to which the tool is secured by the ordinary clamps k. This tool-block is arranged to slide on undercut ways on the under side of the tool-slide E and can be 20 moved in and out by means of an ordinary feed-screw. (Not shown.)

On the upper end of the hub of the gear-wheel g, carried on the upper end of the screw-shaft F, is a positive clutch-face, with which 25 engage the teeth of the clutch-sleeve L. The upward movement of this clutch-sleeve is limited by a nut l, screwed onto the end of the feed-screw F.

A lever L', pivoted at l' to an upright B' 30 on the standard B, is connected to a vertically-arranged operating-rod L², guided at its lower end in a bearing b⁴ at the base of the standard, so that any vertical movement imparted to this rod will throw the clutch into 35 and out of gear with the sleeve, so that the feed can be instantly stopped or started by vertically moving the rod L². The lever L' extends beyond the clutch-sleeve and is connected to a rod l², which works in a bearing l³ 40 on the standard B; acting as a guide for the lever. This depending rod l² extends in position to be struck by the carriage at its extreme upward movement, and the rod at the opposite end of the arm, which is guided in 45 the base of the machine, has a collar l⁴, which is arranged to be struck by the carriage at its extreme downward movement. This is a safety device to throw the clutch out of gear, and consequently stop the feed of the screw-shaft controlling the movement of the carriage 50 when the carriage is in either of its extreme positions. This is especially advantageous where a belt or some other part of the mechanism should break and the carriage 55 would not be shifted at the proper time.

The carriage D is preferably counterbalanced by a weight D' sliding at the back of the machine, (shown by dotted lines in Fig. 2,) and the upper end of this weight is connected to the upper end of the carriage by 60 ropes or chains p p, which pass around

wheels p' p' on a shaft P, mounted in bearings on the standard.

I claim as my invention—

1. The combination in a slotting-machine, 65 of a standard, a driving-shaft carried thereby, a vertical feed-screw on the standard, a horizontal shaft on the standard, the same having means whereby it is driven in either direction from said driving-shaft, gearing 70 connection between said horizontal shaft and the feed-screw, means for changing the direction of rotation of said horizontal shaft, a rod for actuating said rotation-changing means, adjustable blocks on said rod, a carriage on 75 the standard movable by the screw, an arm on the carriage placed to be engaged by the blocks on the rod and a clutch for coupling the driving-shaft to the screw, with a second rod for operating the clutch, said latter rod 80 having means placed to be actuated by the carriage but beyond the normal range of action thereof, substantially as described:

2. The combination of a standard, a feed-screw, means for driving said screw from a 85 source of power, means for changing the direction of rotation of the screw, a carriage reciprocable by the screw upon the standard and controlling said direction-changing means, a tool-slide on the carriage, automatically-operating feed mechanism therefor including a rail on the standard, adjustably-mounted blocks on said rail, an arm on the carriage placed to engage said blocks, and a pawl-and-ratchet connection between said 90 arm and the tool-slide feed mechanism, one of said blocks being placed to engage said arm and thereby cause operation of said mechanism, and the other being placed to positively engage the arm to restore it to its 95 normal position after such operation, substantially as described.

3. The combination in a slotting-machine, 100 of a standard, driving mechanism, a carriage on the standard, a tool carried by the carriage, mechanism for operating said carriage, a clutch for coupling the operating mechanism to the driving mechanism, a lever controlling the clutch, a rod on one arm of the lever in the path of the carriage on its upward stroke and a second rod also connected to the lever and having a projection in the path of the carriage on its downward stroke, substantially as described.

In testimony whereof I have signed my 115 name to this specification in the presence of two subscribing witnesses.

CHARLES C. NEWTON.
